UNITED STATES PATENT OFFICE

156,777

MADONNA CANDLEHOLDER

Cleo V. Sears, Ashtabula, Ohio, assignor to Will & Baumer Candle Co., Inc., Syracuse, N. Y., a corporation of New York

Application April 1, 1949, Serial No. 1,765

Term of patent 14 years

(Cl. D48—2)

To all whom it may concern:

Be it known that I, Cleo V. Sears, a citizen of the United States of America, and resident of the city of Ashtabula, in the county of Ashtabula and State of Ohio, have invented a new, original, and ornamental Design for a Madonna Candleholder, of which the following is a specification, reference being had to the accompanying drawing, forming part thereof.

In the drawing:

Figure 1 is a perspective view of a Madonna candleholder, showing the front and left side of my new design, the right side being substantially similar to the left; and

I claim:

The ornamental design for a Madonna candleholder, substantially as shown and described.

CLEO V. SEARS.
